UNITED STATES PATENT OFFICE.

WILLIAM R. KINNEAR, OF COLUMBUS, OHIO.

METALLIC CEILING.

SPECIFICATION forming part of Letters Patent No. 406,048, dated July 2, 1889.

Application filed November 16, 1888. Serial No. 291,053. (No model.)

To all whom it may concern:

Be it known that I, WILLIAM R. KINNEAR, a citizen of the United States, and a resident of Columbus, in the county of Franklin and State 5 of Ohio, have invented new and useful Improvements in Metallic Ceilings, of which the following is a full and exact description, reference being had to the accompanying drawings, making part of this specification.

10 This invention relates to improvements in metallic ceilings, and more especially to the structure for hanging the same; and it has for its objects to provide means by which the ceiling may be suspended from a metallic frame-work, and to form a structure at once 15 light and strong.

In the drawings, Figure 1 is a plan view of the ceiling to which this invention is applied. Fig. 2 is a plan view of the under side of the 20 hanging structure, the ceiling being removed. Fig. 3 is a plan view of the upper side of the hanging structure, the ceiling being removed, showing, also, a section of a T-rail, to which the ceiling is hung. Fig. 4 is a detail view 25 in perspective of the hanging-strips separated in order to show the construction. Fig. 5 is a detail view in section of the hanging-strips and panels composing the ceilings, showing the manner of fastening the two together. 30 Fig. 6 is a detail view of an alternative means for fastening the same. Fig. 7 is a detail view in section of the device for attaching the hanging-strips to the structure of the building. Fig. 8 is a detail view of the device in 35 perspective. Figs. 9, 10, and 11 are detail views in elevation of alternative devices for the same purpose. Fig. 12 is a detail view, in section, in which is shown the manner of suspending the hanging-strips when the building 40 structure is of wood and the hanging-strips are of metal.

The description of the ceiling shown in the drawings is contained in a patent granted to me August 21, 1888, and numbered 388,285.

45 The present invention consists in providing means for hanging this ceiling to metallic structures.

In this class of structure the floors are supported usually by the beams A, which may 50 be of many shapes, according to the structure, as shown in Figs. 9, 10, and 11 of the drawings. Over these beams is laid the floor, and

from the under side is hung the hanging-strips B and C of the invention. The strips B extend across the room in parallel lines and are 55 fastened to the beams A by means of any one of the devices E shown in the drawings. In practice I prefer to use the device shown in Figs. 7 and 8. The said strips are shaped 60 from sheet-iron in the form of a channel, and provided at the open edges with the flanges D, which lie close to the lower edges of the beams A. These flanges may be turned in or out, so as to extend into the grooves E' at the sides of the said devices E shown in 65 Figs. 7 and 8. By means of this construction the devices may be shifted along the length of the strip, the flanges acting as guides. In the panels shown in the drawings the lower 70 faces of the channeled strips are flat; but in some designs of the panels along the edges I run a raised molding, and in this event the lower faces of the strips may be provided with moldings, if so desired.

The devices E of the form shown in Figs. 7 75 and 8 are, as stated above, provided with the side grooves E'. They are also provided with the depending flange E², which extends between the sides of the strips and form therewith guides for the devices. At the forward 80 end the metal of the devices is struck up to form the extension E³, in shape corresponding with the flange of the beam A, to which it is to be fitted or placed over. The extension is slightly depressed to form a tight joint 85 with the flange of the beam and to draw the strips B to a close contact therewith. To strengthen the said extension, the brace E⁴ is set in between it and the body of the device. In the operation of hanging the said strips 90 the devices E are disposed one to a beam and faced in opposite directions to thrust against each other. The strips are thus prepared by sliding the devices E on them and placing them so as to come on the side of the beam 95 desired. When thus prepared, the strips are raised against the beams A and the devices forced against the beams, with the extensions E³ extending over the flanges on the said beam. In this position and for the better security of the strips the devices are maintained 100 in position by indenting the sides of the grooves E' and flanges D when in position, and thereby holding the devices on the strips

and preventing them from becoming detached from the beams.

The devices shown in Figs. 9, 10, and 11 are the same as above described, being applied to different forms of beams A.

In Fig. 12 of the drawings is shown a method of hanging the ceiling wherein I use metal strips B and C on a wooden structure. This method renders the work better, as it is lighter, in cases where the strips B and C are by design large. In this construction the flanges D of the strips are punctured, and screws are driven through the punctures into the wood to sustain them. In this ceiling the strips C extend between and are supported by the strips B. They are set apart the dimension of the panel as it extends parallel to the strips B. In this way the strips B and C, when suspended, form pockets for the reception of the separate panels of the ceiling. Before suspending the strips B they are provided at the required intervals with slots cut in the sides. When the first line of the strips B is suspended, and before the second is put in position, the cross-strips C are placed between, so that the lugs C', which are formed on the sides of the said strips at the ends, are inserted in the slots formed in the sides of the strips B. As the succeeding line of the strips B is placed in position, the lugs in the free ends of the strips C are inserted in the slots in that strip, and thus held firmly in position where the latter strip B is secured, and so on, placing the strips C in position between the hanging of the strips B until the top of the room is covered with a series of pockets, as shown in Fig. 2 of drawings. At predetermined intervals the strips B and C are provided in the channels with screw-threaded perforations in the lower face. Two alternative methods of forming the perforations above referred to are shown at Figs. 5 and 6. In the one a screw-nut F is soldered or otherwise fastened over the perforations, while

in the other the thread is formed in an elongated piece of metal, the ends of which pass through slots in the sides of the strips and are there fastened by turning the ends down and thus securing the pieces against moving. The ceiling is suspended to the strips in single panels, which are joined, as described in the patent above referred to. Where the edges lap, perforations are provided in them in line with the screw-threaded perforations in the hanging-strips. Screws are now driven through the panels and engage the threaded perforations in the strips B and C, and the hanging of the ceiling is completed.

In some structures, when it is desired to make them more impervious to fire, a fire-non-conducting material is poured in on top of this ceiling as a backing. This, however, I consider in the large majority of cases unnecessary.

What I claim is—

1. In a ceiling such as described, the hanging structure, consisting in the combination of the strips B being suspended from the beams of the building structure, the strips C, extending between the said strips B, and suitable connections for suspending the strips C upon the strips B, substantially as set forth.

2. In a ceiling such as described, the hanging structure, consisting in the combination of the strips B, suspended from the beams of the building structure and provided at predetermined intervals with slots in the sides, and the strips C, extending between the strips B and provided upon their ends with lugs C', for being inserted in the said slots in the sides of the strips B, to support the strips C, substantially as set forth.

In testimony whereof I have hereunto set my hand this 5th day of November, A. D. 1888.

WILLIAM R. KINNEAR.
